UNITED STATES PATENT OFFICE.

JOHN BAUER, OF DETROIT, MICHIGAN.

STRIP MOISTENER.

Application filed January 12, 1922. Serial No. 523,854.

To all whom it may concern:

Be it known that I, JOHN BAUER, a citizen of the United States, residing at Detroit, in the county of Wayne and State of Michigan, have invented a new and useful Strip Moistener (Case B), of which the following is a specification.

This invention relates to strip moistening devices, and more particularly to moistening devices designed for moistening the glued surface of paper strips employed in wrapping packages.

The primary object of the invention is to provide a moistening device wherein the moisture will be applied evenly throughout the width of the strip to insure the strip adhering to the package, to which the strip is applied.

A further object of the invention is the provision of means for supplying liquid to the liquid distributing rolls at predetermined intervals, at the will of the operator.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 illustrates a longitudinal view through the device constructed in accordance with the present invention.

Figure 2 illustrates a front elevational view of the same.

Referring to the drawings in detail, the reference character 5 designates the base or main reservoir of the device which is designed to contain the moistening liquid, which reservoir has communication with the supply tank 6, as through the opening 7, the supply tank 6 being provided with a threaded extension to be positioned in the threaded recessed portion 8 of the reservoir 5.

This reservoir 5 is provided with a reduced portion 9 for the reception of one end of the tubular member 10, which has its upper extremity disposed within the sleeve 11 which houses the spring 12 that has its upper extremity contacting with the movable valve block 13, carrying the nozzle 14.

Supported within the tubular member 10 is a wick member 15 formed of loosely woven material which is designed to conduct moisture from the reservoir 5 and deliver the same to the nozzle 14, and at the same time retard the flow of liquid through the member 10 when the device is inverted whereupon the moistener is transferred to the roll 16 which is supported directly above the nozzle 14 and which operates over the inclined surface 17 thereof.

Supported at the upper extremity of the tubular member 10 is a delivering nozzle designed to deliver the strip, and in this nozzle are rotatably supported the rolls 18 and 19, the roll 19 being the delivering roll and which contacts directly with the glued surface of the paper strip under operation.

As shown, the delivering nozzle indicated by the reference character 20 is provided with a pair of openings formed in one of the walls thereof, the upper opening adapted to accommodate the strip indicated by 21 so that the strip may pass into the delivering nozzle, and over the delivering roll 19, the roll 18, which is disposed adjacent to the roll 19 being provided with a means to permit the roll to be rotated by the operator, whereby the strip 21 is fed through the delivering nozzle and over the delivering rolls 22.

Having connection with the reservoir 5 is an upwardly extending supporting arm 23 which has its upper end extending outwardly as at 24, to provide a support for the arm 25, which in turn supports the knife 26 that operates through the slot 27 formed in the delivering nozzle 20. The arm 25, has pivotal connection with the arm 23 to permit the knife to move laterally to sever the strip 21 after the same has passed the moistening roll 19.

Disposed under the arm 25, is an arm 28 which is pivotally connected to the arm 23 as at 29, the inner extremity of the arms supporting the roller 16 in a manner so that the roller may be moved across the upper end of the nozzle 14, to open and close the nozzle, and control the flow of liquid through the nozzle. This arm 23 extends to a point overlying the main tank 6, and since the arm 23 is formed of resilient material, it is obvious that upon movement of the arm 28, the roller 16 may be moved to accomplish its purpose.

Supported by the arm 23, adjacent to the

lower extremity thereof, is a shaft 30 on which is mounted the roll of paper which is passed through the device, there being provided a coiled spring indicated at 31 5 for normally holding the roll of paper in its proper position.

From the foregoing it is obvious that in the operation of the device, the device is inverted by the operator and the arm 28 10 is moved to cause the spring 12 to compress the member 15, and cause the liquid to flow through the nozzle 14, whereupon moisture is transferred to the moisture delivering roll 19, and upon movement of the roll 18, 15 the strip 21 is fed through the device, whereupon the same picks up the moisture from the roll 19 and passes outwardly over the rolls 22.

It follows that upon movement of the 20 arm 25, the knife 26 is moved transversely to sever a portion of the strip.

What is claimed as new is:—

1. In a device of the character described, a main reservoir, a tank for supplying 25 moistening liquid to the reservoir, a tubular member supported by the main reservoir and communicating therewith, a movable delivering nozzle positioned above the tubular member, said nozzle having an inclined delivering end, a movable roll adapted to operate over the inclined end of a nozzle to receive moistening liquid therefrom, and a roll adapted to receive moistening 30 liquid from the first mentioned roll.
2. In a device of the character described, a main reservoir, a tank for supplying moistening liquid to the main reservoir, a tubular member supported by the main reservoir and communicating therewith, a 35 wick in the tubular member, a moistening roll disposed above the wick and adapted to receive moistening liquid from the tubular member when the device is inverted, and

manually controlled means for compressing the wick to cause liquid to pass therefrom. 45

3. In a device of the character described, a main reservoir, a tank for supplying moistening liquid to the main reservoir, a tubular member in communication with the main reservoir, a wick in the tubular member, a spring supported nozzle disposed above the wick, said spring adapted to engage the wick, and means for moving the spring to compress the wick, and cause liquid to drop therefrom when the device is 50 inverted.

4. In a device of the character described, a main reservoir, a tank for delivering moistening liquid to the main reservoir, a tubular member communicating with the main reservoir, a wick disposed in the tubular member, a moistening roll disposed above the tubular member, and means for compressing the wick to cause liquid to flow 55 from the tubular member when the device is inverted, and means for delivering a strip to the moistening roll.

5. In a device of the character described, a main reservoir, a tank for supplying moistening liquid to the main reservoir, a 60 tubular member communicating with the main reservoir, a wick in the tubular member, a sleeve mounted on the tubular member, a movable member operating over the sleeve, a spring in the sleeve, and engaging 65 the wick to compress the wick when the movable member moves towards the tubular member, means in the movable member for delivering a moistening liquid.

In testimony that I claim the foregoing 70 as my own, I have hereto affixed my signature in the presence of two witnesses.

JOHN BAUER.
